CLEAN-OUT DEVICE

David Dumas, Bakersfield, Calif.

Application February 25, 1935, Serial No. 8,048

1 Claim. (Cl. 285—90)

The present invention relates to an improvement in clean out devices.

More particularly the invention is directed to an article of manufacture to be used in connection with a liquid or gaseous pressure supply means for use in cleansing smokers' articles, such as pipes and cigarette holders, to unclog sink drains, and to open up gasoline feed lines on automobiles when the gasoline flow becomes interrupted for some reason.

The invention further relates to the combination, with the other means for connecting up with a liquid or air pressure supply, of an apertured cap which can be used in such a manner as to adapt the device for application to pressure supply tubes of a greater and also of a less diameter than would otherwise be possible.

An important object of the invention is to provide in a device of the above character, an improved plug element having both an external and internal conical taper to adapt it for efficient use in making connections with air or liquid supply conduits of various diameters.

Other objects, advantages and features of the invention will hereinafter appear.

With these ends in view this invention consists in the details of construction and combination of elements hereinafter set forth and then specifically designated in what is claimed.

In order that those skilled in the art to which this invention appertains may understand how to make and use the same, the construction will now be described in detail.

Referring to the accompanying drawing, which illustrates what are at present deemed to be preferred embodiments of the invention,

Fig. 1 is a side elevation of the device which, as shown in this view, may be constructed internally in accordance with either of the embodiments thereof illustrated in Figs. 2 and 4. The dotted lines indicate a smoking pipe and an air hose in operative relations to the device.

Fig. 2 is a vertical mid-section of the device shown in Fig. 1.

Fig. 3 is a broken perspective of the cap or collar shown in the upper portion of Fig. 2.

Fig. 4 is a perspective of a different embodiment from that shown in Fig. 2, portions being broken away in order to show internal construction more clearly. In this view an air valve is shown in dotted lines, ready to be applied to the device.

Fig. 5 is a sectional view of a third embodiment showing the same positioned in the top of a sink drain ready to apply a flushing liquid.

Referring in detail to the drawing, the conical rubber or cork plug 7 shown in Fig. 2 is vulcanized to a pipe 8 which extends axially therethrough from the small end thereof and projects considerably beyond the large end thereof. The small end of this plug is shown tapered to substantially a knife edge around the end of the pipe or tube 8. A cap 9 having a circular end opening 10 is shown fitted upon the projecting end of the tube 8 for the purpose of bringing the tube 10 up to the desired or standard diameter whereby it is adapted to engage in a cooperating manner with an air hose valve 11 when it is desired to clean out a pipe 12. The conical face makes the plug adaptable for use with smokers' pipes, 15 the bowl openings of which vary in both diameter and depth. The elasticity thereof makes it adaptable for use with such pipes whose bowls are irregularly caked.

The internal diameter of tubing varies, for example tin tubing has a different inside diameter than standard tubing and although tin tubing is adaptable for use in constructing my plugs it is unadapted, without modification, to operate air valves like those which are used at service stations for filling automobile tires. For this reason it is necessary to bring the inside diameter or outside diameter to a size adapted for contacting with the air valve in using the device. Therefore when standard tubing of the right size is 30 used in constructing the device (although such tubing costs more) this novel plug will be constructed without the cap as shown in Fig. 4.

In Fig. 4 is shown a plug 13 shaped like the plug 7 except that the small end thereof is of a sufficient diameter to provide room therein for a conical recess 14 which tapers inwardly from that end of the plug. There extends axially into this plug from its large end, a tube 15, which is vulcanized to the plug and which projects somewhat from its large end.

In Fig. 4 the plug is shown with its conical recess fitted over the end of a tube 16, and an air valve 17 is indicated in dotted lines in readiness to be applied to the device to direct a blast of air 45 into said tube 16. The conical recess 14 adapts this form of the device for being applied in a substantially air tight manner to tubes varying considerably in diameter.

The embodiment of the invention shown in Fig. 5 differs from that shown in Fig. 2 in that the plug 20 has a circumferentially ribbed tube 21 extending axially therethru and said tube has a diametrically enlarged portion 22 near its large end which is internally screw threaded to screw 55

on to the coupling member 24 of a garden hose 25. The part 22 terminates in a peripheral outwardly directed flange 23 abutting against the adjacent end of the plug. In this view the device is shown screwed on to the garden hose 25 and inserted into the mouth of the drain pipe 26 of a sink 27, preparatory to flushing out said drain pipe.

In the construction shown in Fig. 4 the mouth 10 of the frusto-conical recess 14 is of nearly as great a diameter as the external diameter of the small end of the plug thus providing a narrow annular compressible and expandable lip 30 at that end of the plug. Said lip may be diametrically contracted or expanded according to requirements in making a fluid or air tight fit into or over parts having passages into which the liquid or fluid is to be forced.

In Fig. 3 the opening 10 is formed by upsetting the end of the tube 8 in such a manner as to form an upwardly directed circumferential flange 10x.

It is to be understood that the forms of my invention herewith shown and described are to be taken as preferred examples of the same, and that various changes in the shape, size and arrangement of parts may be resorted to without departing from the spirit of the invention, or the scope of what is claimed.

Having in this case described my invention, I claim:

Means for coupling an air hose valve to a tube, 10 comprising a conical plug of elastic material having an axial bore extending therethrough, a metal tube inserted in said bore, said tube projecting from one end of said plug and adapted to engage and open said valve, the bore at the other end 15 of the plug being adapted to receive a second tube, said bore being taperingly increased in diameter from the enclosed extremity of the first tube to the smaller end of the plug to adapt it for use on tubes of varying sizes. 20

DAVID DUMAS.
